UNITED STATES PATENT OFFICE.

PERCY H. THOMAS, OF UPPER MONTCLAIR, NEW JERSEY, ASSIGNOR TO COOPER HEWITT ELECTRIC COMPANY, OF HOBOKEN, NEW JERSEY, A CORPORATION OF NEW JERSEY.

VAPOR ELECTRIC APPARATUS.

1,214,613.

Specification of Letters Patent. Patented Feb. 6, 1917.

Application filed September 12, 1912. Serial No. 719,925.

To all whom it may concern:

Be it known that I, PERCY H. THOMAS, a citizen of the United States, and resident of Upper Montclair, county of Essex, State of New Jersey, have invented certain new and useful Improvements in Vapor Electric Apparatus, of which the following is a specification.

My invention relates to the operation of mercury vapor devices, more particularly when run under high pressure, in constant current circuits. Constant current circuits are utilized frequently and without difficulty in connection with consumption devices characterized by an absorption of voltage which increases only with rising current. When the serially operated device is, however, such that the voltage may rise without an increase in current, simple series operation has the tendency to be unstable as will hereinafter be explained more particularly.

The object of the present invention is to secure a type of series circuit or designs of mercury vapor device such as can be successfully operated on a constant current circuit.

The particular systems made use of will be explained more fully in connection with the several figures of the drawings, in which—

Figure 1 illustrates a constant current circuit feeding mercury vapor apparatus; and Fig. 2 shows another such system adapted to alternating or direct current. Fig. 3 shows a specially formed lamp adapted to this service; and Figs. 4 and 5 show characteristic voltage-current curves.

In Fig. 5 I show a characteristic curve representing a device having a voltage current relation which requires no correction for series operation. It will be noted from this curve that an increase in voltage is obtainable only with an increase in current and that if the current be held steady the voltage will not exceed a certain amount. Fig. 4, on the other hand, shows a characteristic voltage current curve which will be found to cause unstable operation in constant current series circuits. For suppose the device to be

operating at the point marked *p*, Fig. 4: While the voltage is coming up during the warming process from the lower voltage to this point there is an increase in voltage whenever there is an increase of current. 55 But, a further increase in voltage will occur in case of a continued rise of temperature without an increase in current and even with an actual decrease of current. This means in the case of a serially operated mercury 60 vapor apparatus that the vapor pressure rises so fast from the point *p* with increased temperature of the lamp that the voltage absorbed in the vapor and hence the heat produced therein increases so rapidly as to 65 maintain all radiation losses and support the actual vapor pressure with a lower current than would be sufficient to maintain the lower radiation losses at a somewhat lower 70 temperature in the device and hence lower 75 vapor pressure therein. When such lamps as those represented by the characteristic of Fig. 4 are operated in series on a constant current circuit trouble follows for if any one lamp is so constituted to run a little 80 hotter or happens for any reason to get a little hotter than the others its vapor pressure will immediately rise rapidly and since the current is maintained by the generator its pressure and voltage goes up very rapidly until this device is injured or the series of lamps is extinguished.

Considering now Fig. 1, in which the individual mercury vapor devices 1, 1, 1, have a characteristic curve like that shown in Fig. 4, I show a method of constant current operation secured by the use of shunt circuits 2, 2, 2, which are automatically closed in shunt with the lamps 1, 1, 1, through the resistances, 3, 3, 3, by the thermostats, 4, 4, 4, 85 or in one circuit by this thermostat whenever a lamp voltage tends to an excessive rise. The thermostat 4, when raised to a certain temperature by means of the elevation of temperature of the lamp to which it 90 is adjacent, will lower the part 6 until the contact 5 closes the shunt 2. The resistance 3 is so adjusted that the current then remaining in the lamp will drop slightly below the minimum danger current, thus per- 100

mitting this lamp to cool off. In some circuits these shunts would be thrown off and on more or less irregularly and thus preserve a perfect balance, on the average, between the lamps.

In Fig. 2, I show a somewhat similar system, in which the lamp 7 is adapted for use on alternating current. Shunts are closed through the resistances, 8, 8, by way 10 of the cutouts, 9, 9, by the action of the magnets, 10, which are connected around the several lamps and thus measure the voltage thereon. The resistances, 11, 11, control the current in the magnets, 10, 10. 15 The operation of this system is clear from that of Fig. 1, the chief difference being that in Fig. 2 the shunt circuit is closed by an electromagnet responsive to excess voltage on the lamp itself instead of by a thermostat. The currents through the resistances 8 are adjusted to abstract sufficient current from the lamp to prevent its overheating due to the full current flow, while the resistance 11 is adapted to control the 20 magnetizing current of the coil 10.

Fig. 3 shows a lamp of the general type shown at 1 and 7 in Figs. 1 and 2, but modified to have a voltage current characteristic such that the voltage at a critical point 30 shall be increased only with considerable increase in current. In this lamp the light-giving tube 12 is somewhat similar to those usually supplied with high pressure mercury vapor lamps while 13 is the cathode 35 and 14 is the anode. 15 is a condensing chamber, 16 an additional condensing chamber connected with 15 through the constriction 17. 18, 18 are mercury-sealed leading-in plugs for carrying the current to the mercury. As this lamp is shown for high pressure operation, it should preferably be constructed of quartz or some hard glass. If desired, I may use a return tube, 20, shown 40 dotted, to carry condensed mercury from the auxiliary condensing chamber 16 to the electrode 14. The cooling chamber 19 may be attached to the cathode to absorb 45 heat therefrom and assist in the maintaining of the normal mercury level in this electrode. The operation of the chambers 16 and 15 is somewhat as follows: When the device is started up cold, the vapor pressure in the light giving path is relatively 50 low and a small weight of mercury vapor occupies a large volume. This vapor is condensed rapidly in the chamber 15. Since, however, a large excess of heat is generated 55 in the low temperature condition of the device on account of the relatively slow radiation into the air at such temperatures, the mercury rapidly heats up, thus increasing 60 the vapor pressure very materially in the tube 12 and the chamber 15. A certain amount of mercury escapes through the

throat 17 into the chamber 16 but in view 65 of the narrowness of the throat and the relatively low pressure, a comparatively small weight of mercury vapor actually escapes, but, as the tube heats up to say at or near atmospheric pressure, a given volume of 70 mercury represents a much larger weight of mercury and very appreciable quantities of mercury escape into the condensing chamber 16 where they are condensed by the heat radiating capacity of this chamber. 75 This, in effect, changes the characteristic of the lamp tending to lower its voltage for any given current above the critical point where the amount of mercury escaping into the chamber 17 becomes material so that 80 this characteristic instead of being, as it would otherwise be, similar to that shown in Fig. 4, it becomes more like that shown in Fig. 5.

While I have shown some specific methods 85 of gaining stability in these series circuits with containing devices having naturally straight upward characteristics, I do not wish to limit my invention to these particular features, for my invention is broader 90 including the utilization of any specific means for correcting the tendency introduced by the use of constant current for individual devices to take abnormal temperatures or pressures. I do not wish to 95 limit myself to mercury vapor apparatus, though my invention is especially adapted to this apparatus, nor do I wish to confine myself to a mercury electrode rather than one of some other appropriate material. 100 Neither do I wish to limit myself to lamps operating in quartz tubes nor at the specific pressures here described. It is not necessary that the characteristic of such a lamp turn backward to the extent shown in the 105 curve of Fig. 4; this figure, however, gives a good example of a device unstable on constant current.

I claim as my invention:

1. A mercury vapor apparatus comprising a container sealed and exhausted to a high degree of purity having a light-giving portion, a mercury electrode therein, a condensing chamber in communication with the vapor space of said apparatus, a second 110 condensing chamber in communication with the interior of said lamp through a restricted opening adapted to pass a material weight of mercury only under normal operating pressure.

2. A mercury vapor apparatus comprising a container, electrodes therein, electrical means for operating such apparatus, and a condensing chamber connected thereto by a neck having an opening sufficient in area 115 to permit the free passage of mercury thereto only above the minimum normal operating pressure.

3. A mercury vapor lamp comprising a light giving container and suitable electrodes therein including a supplementary condensing chamber and a communicating passage thereto having an area of opening capable of passing sufficient vapor to operate said condensing chamber only under normal operating pressure in said lamp.

Signed at New York, in the county of New York, and State of New York, this 9th ~~10~~ day of September, A. D. 1912.
